PROTECTIVE COSMETICS

Samuel Isermann, Summit, Ernst Ohlsson, Jersey City, and John W. Orelup, Summit, N. J.

No Drawing. Application January 4, 1935,
Serial No. 426

5 Claims. (Cl. 167—90)

Our present invention relates to improvements in protective cosmetics. It is well known that over-exposure of the body to direct radiation from the sun is apt to cause acute and chronic dermatitis, blisters, severe burns, as well as such disagreeable minor effects as: mottling of the skin, pigment anomalies, freckles, etc.

The development of a pleasing tan coloration of the skin is much sought after but can be obtained only by allowing the skin to gradually develop its own protective pigmentation by even deposits of melanin. The best way to accomplish this is by reducing the high intensity of the ultra violet in the solar radiation. The intensity of the ultra violet in the sun radiation between 2900° and 4500° Ångstrom units, is very high, amounting to 17% of all the radiation received. The intensity of the region below 2900° amounts to only 1.8%.

Heretofore, workers in the art have been handicapped by the lack of satisfactory means for quantitatively measuring the screening effect of thin films of active materials so that the use of substances heretofore proposed has been based largely on theoretical grounds, it being assumed that those substances which show absorption in the ultra violet region would be practical for the purpose of protecting the skin.

We have devised such a means which comprises a filter, such as fused calcium phosphate colored with oxides of nickel and cobalt, which admits only physiologically active rays and rejects the visual and infra red rays. The radiation thru this filter is then measured by means of a suitable photo-electric cell, as for example, a copper oxide cell, connected to a highly sensitive microammeter of low internal resistance.

To test a given substance it is merely necessary to spread a thin film of the same on the filter, expose the coated filter to the sun and record the reading which is thereupon compared with a reading obtained under the same conditions without the film and in this way a percentage value obtained. The readings of the microammeter are directly proportional to the intensity of the ultra violet radiation of wave lengths 2900 to 4000° Ångstrom.

By employing this test, it has been found that many substances which have heretofore been proposed, such as benzyl cinnamate, benzyl salicylate, menthyl salicylate, aesculetine, salts of quinine, and umbelliferon, although on theoretical grounds capable of a substantial amount of ultra violet absorption, are practically valueless

when used in a thin film even in concentrations in excess of what could be tolerated by the skin. Thus, in the undiluted state, menthyl salicylate shows only 10% absorption of the ultra violet, benzyl salicylate undiluted 17%, benzyl cinnamate 20%.

As can be seen the use of these compounds would be of no appreciable benefit; moreover, the concentrations required even for this small degree of absorption are too high for practical use. Coating the body with undiluted substances of this type would cause serious physiological disturbances.

After examining a large number of substances, we have found that in thin films even extremely small quantities of amino and substituted amino-ortho-benzoic acids have the remarkable property of absorbing from 50% to 80% of the ultra violet radiation of the sun in the region between 2900° and 4000° Ångstrom. Percentage concentrations which are effective are as low as .01%. Of course, larger concentrations may be used, for example, up to 5%. In most cases for an oil type cosmetic it is necessary to form an oil soluble derivative. This oil soluble derivative may be produced by uniting the active ingredient with a fatty acid, as for example stearic acid or oleic acid or mixtures thereof.

An advantage of our improved compounds is that they are substantially odorless and colorless. The compounds substituted in the amino group are practically odorless in contradistinction to those compounds substituted in the carboxyl group which are strongly odorous. The active ingredient which we prefer is benzyl-amino-ortho-benzoic acid. Also effective are the methyl- and di-methyl-amino-ortho-benzoic acids; the butyl, propyl, amyl, and higher derivatives: as the lauryl, myristyl, cetyl compounds.

The following examples illustrate the invention:

I

Benzyl-amino-ortho-benzoic acid is dissolved in peanut or other oil in the amount of 1/2 to 1%, and a suitable amount of color and perfume is added.

II

A 1% solution of dimethyl amino-benzoic acid is formed in 20% almond oil and 80% mineral oil with color and perfume to suit.

III

Ortho-amino-benzoic acid stearate is prepared as follows: 14 lbs. ortho-amido-benzoic acid is

melted with 30 lbs. stearic acid heated to 80° C. until mass is homogeneous. The product is cooled and pulverized. A 2% solution is thereupon formed in mineral oil.

5 We claim:

1. A cosmetic effective in thin films to retard ultra violet absorption containing as an active ingredient an amino or substituted amino-ortho-benzoic acid in concentrations of less than 5%.

10 2. A cosmetic effective in thin films to retard ultra violet absorption containing as an active ingredient benzyl-amino-ortho-benzoic acid in concentrations of less than 5%.

15 3. A protective cosmetic containing as an active ingredient an ortho-amino-benzoic acid and being effective in thin films to absorb from 50% to 80% of ultra violet rays of the sun in the

region between 2900 degrees and 4000 degrees Angstrom when said active ingredient is present in an amount not substantially greater than 5%.

4. A cosmetic effective in thin films to retard ultra violet absorption containing as an active 5 ingredient a fatty acid compound of an amino or substituted amino-ortho-benzoic acid in an oily vehicle in concentrations of less than 5%.

5. A cosmetic effective in thin films to retard ultra violet absorption containing as an active 10 ingredient an amino or substituted amino-ortho-benzoic acid in an oily vehicle in concentrations of less than 5%.

SAMUEL ISERMANN.
